JURJEN S. HIGH, OF WILKINSBURG, PENNSYLVANIA, ASSIGNOR TO WESTINGHOUSE ELECTRIC & MANUFACTURING COMPANY, A CORPORATION OF PENNSYLVANIA

TRANSLATING DEVICE

Application filed October 20, 1927. Serial No. 227,409.

My invention relates to translating devices, and it has particular relation to devices of the type now commonly known as loud speakers.

5 It has been established by previous workers in the art that improved results may be obtained from loud speakers of the type utilizing large conical or plane diaphragms if means are provided to prevent air from circulating between the front and the rear of the diaphragm at low frequencies. Such means may take the form of a baffle encircling the diaphragm, as shown in the patent to Rice, No. 1,631,646, or the rear of the dia-

10 phragm may be located in a substantially closed chamber or a chamber filled with a damping material, such as felt or the like.

In the event that the loud speaker is a constituent part of a radio receiving set of 20 the console type, a wall of the cabinet may conveniently be utilized as the baffle. When it is desired to construct a small, self-contained loud speaker, however, it is inconvenient to surround the diaphragm-housing by a baffle of sufficiently large diameter to accomplish any useful purpose, and this inconvenience is accentuated if the loud speaker is of the small type designed to be suspended 25 from the wall of a room.

30 It is, accordingly, an object of my invention to provide a loud speaker with self-contained baffle elements that do not materially increase the space occupied by the apparatus when such apparatus is mounted for use.

35 Another object of my invention is to provide a loud speaker incorporating baffle-devices that effectively replace the damping materials referred to above.

40 Another object of my invention is to provide a loud speaker of the wall type in which is embodied an inconspicuous baffle-device.

Another and more specific object of my invention is to provide a loud speaker comprising a baffle-device that has only a slight damping effect.

45 The baffle-device that I have found most suitable for incorporation into a loud-speaker of the wall type comprises a plurality of nested circular partitions surrounding the rear face of the diaphragm, and it is so

arranged that the sound waves emanating from the said rear face are caused to travel in a tortuous path before reaching the front of the diaphragm and there commingling with the sound waves emanating therefrom. 55 By properly proportioning the partitions, the length of the path from the rear of the diaphragm to the front thereof may readily be adjusted to the best possible value, and it is preferably made approximately equal to a 60 quarter wave-length of the longest useful sound wave to be reproduced.

In addition, I have found it useful, in some cases, to so proportion and space the baffle-partitions that the passage afforded thereby increases in area in a manner somewhat analogous to the increase in cross-sectional area of the exponential horn disclosed in the patent to Hanna and Slepian, No. 1,623,561, 65 in order that the damping imposed on the rear surface of the diaphragm shall be largely independent of frequency. 70

75 Among the novel features of my invention are those particularly set forth in the appended claims. The invention itself, however, both as to its organization and its method of operation, together with further objects and advantages thereof, will best be understood from a consideration of the following description of certain specific embodiments, taken in connection with the accompanying drawings, in which:

80 Figures 1 and 2 are cross-sectional and front elevational views, respectively, of a preferred embodiment of my invention, and 85

Figs. 3 and 4 are analogous views of an alternative form thereof.

90 The device illustrated in Figs. 1 and 2 comprises a circular base plate 1, having a marginal rim 2 through which extend a plurality of bolts 3 by which the device may be affixed to a wall 4. In lieu of the bolts 3, the device may, if desired, be provided with any other convenient suspension means.

95 A circular cover plate 5, which may be flat or concaved toward the center, as shown, is mounted in spaced, parallel relation to the base plate 1, the mounting means therefor comprising a plurality of spacing devices 6, each provided with an internally threaded 100

opening into the opposite ends of which extend bolts 7 and 8 that project through countersunk holes provided in the plates 1 and 5.

A large central opening is provided in the cover plate, in order to accommodate a diaphragm 10, which is freely suspended therein from an annulus 11 of velvet, kid, rubber, or equivalent material. The outer edge of the annulus 11 is clamped between the cover plate and a pressure-ring 12, a plurality of screws 13 serving to maintain the ring in position.

In order to actuate the diaphragm, an electromagnetic driving device 14 is provided. This device, which may be of any conventional type, is mounted on the base plate 1, and is operatively connected to the diaphragm by means of a flexible connector 15 of the type disclosed in my copending application, Serial No. 91,738, filed March 2, 1926. The circular diaphragm, which is preferably made of an extremely light, yet rigid material, such as paper or the like, is vibrated as a piston by the driving unit and is not appreciably flexed thereby.

A plurality of circular partitions 16, concentric with the diaphragm opening, project inwardly from the cover plate to within a short distance from the inner surface of the base plate 1. Additional circular partitions 17 project from the base plate to within a short distance from the inner face of the cover plate 5; the partitions carried by each plate alternating radially of the device to define a tortuous sound-passage that repeatedly bends back on itself.

The sound passage, which is indicated by the arrows, may be given any desired length and rate of expansion by properly choosing the number and spacing of the partitions, or baffles 16 and 17. Preferably, the total length of the path from the center of the inner face of the diaphragm to the center of the outer face thereof is made equal to a quarter wave-length of the lowest sound frequency it is intended to reproduce. The mathematical basis for this statement is given to the Rice patent previously referred to and need not be repeated here. It is sufficient to say that, by preventing a free circulation of air between the rear and the front of the diaphragm, the response thereof to low frequencies is greatly improved, and the efficiency of the device is increased.

Although I have shown in the drawing only two such partitions carried by the base and two carried by the cover, it lies within the scope of my invention to provide as many of such partitions as are necessary.

The baffles 16 and 17 have also an additional important function of preventing the diaphragm housing from resonating at any particular frequency. Such resonance effects have, in the past, seriously interfered with the quality of music reproduced by loud

speakers comprising large flat or conical diaphragms. Previously suggested damping devices, such as felt and the like, have not been entirely successful, but by breaking up the interior of the device into a plurality of inter-mingled chambers, each chamber somewhat analogous to a Helmholtz resonator and each having an individual resonance-frequency housing-resonance at any single frequency is prevented, and the response curve 75 of the unit is flattened.

In an alternative form of my invention, the baffle-partitions are so arranged that the sound passage from the rear of the diaphragm to the open air progressively increases in area from the center of the diaphragm radially outward. The increase in area is preferably approximately exponential in character, and the sound passage accordingly tends to damp or load the diaphragm to substantially the same amount, irrespective of frequency, provided the velocity of the diaphragm is maintained a constant.

The modification of my invention in which the sound passage is so arranged that it progressively increases in area, is illustrated in Figs. 3 and 4 and comprises a base 20, which supports, through the agency of a plurality of spacing devices 21, a cover 22 having a large central opening. An annular element 23 is supported from the inner surface of the cover 22, and cooperates with the base to define a circular sound opening that increases exponentially. A conical diaphragm is freely suspended in the opening from a resilient annulus 24 which is held concentric with the opening by a clamping ring 25. A loud-speaker motor 27, of any conventional type, is affixed to the base member 20 and is operatively connected to the apex of the diaphragm.

A plurality of circular partitions 28 surround the driving motor 27, the radial distance between successive partitions increasing toward the periphery of the device. 110 These partitions increase in height progressively, the free edges thereof being arranged to lie in the surface of an imaginary cone which has, at its apex, a slightly more obtuse angle than the apex of the cone diaphragm. 115

The cover plate is provided also with a plurality of concentric depending partitions 29 which are arranged in nested relation to a plurality of additional partitions 30 carried by the base member, the radial distance 120 between adjacent partitions increasing toward the periphery of the device, considered as a whole.

The sound passage, therefore, defined by the several baffle devices, is somewhat obstructed in the vicinity of the rear of the diaphragm by the baffles 28, and the peripheral portion thereof is rendered tortuous by the interleaved or nested relation of the additional partition members 29 and 30. The pro- 130

vision of the partition members 28 directly to the rear of the diaphragm is important in preventing resonance effects from the enclosure while, at the same time, the passage 5 of the sound to the exterior of the device is but slightly hampered thereby.

By reason of the increased spacing between successive partitions, the sound passage may be given any desired rate of cross-sectional 10 increase. In the example illustrated, it will be noted that any radial element of the passage, as defined by the partitions, increases in area from the center of the peripheral outlet. Although this increase in area is not 15 smooth, as is the case in the exponential horn disclosed in the Slepian et al. patent previously referred to, yet, at the same time, it may be made to approximate the rate of increase shown in that patent.

20 The sound passage may be given any desired length by properly choosing the number and spacing of the baffle partitions, as explained in connection with Fig. 1. This length is preferably also made approximately that of a quarter wave length of the longest sound wave it is desired to produce.

A loud speaker, constructed according to my invention, is considerably more efficient than loud speakers of the type wherein the 30 diaphragm is exposed freely to air on both sides thereof and is also more efficient than loud speakers wherein the rear surface of the diaphragm is enclosed by a chamber provided with damping means, such as felt or 35 the like. The load imposed on the diaphragm by a housing constructed according to my invention is quite even over a wide range of frequencies, and pronounced resonance effects are noticeably absent.

40 I have described my invention as being particularly useful in connection with cone or plane diaphragms of large area but it is not restricted to use therewith, being applicable to loud speakers of the type wherein 45 a small metallic diaphragm is directly actuated by electromagnetic means.

It is also entirely feasible to incorporate my invention into a small table, in which event the base-plate 1 shown in Fig. 1, may 50 constitute the table-top. This modification, being sufficiently obvious, is not illustrated.

55 Although I have illustrated only two specific embodiments of my invention, numerous modifications thereof will be apparent to those skilled in the art. My invention, therefore, is not to be limited except insofar as is necessitated by the prior art and by the spirit of the appended claims.

I claim as my invention:

60 1. In a sound-producing device, a diaphragm, means for actuating said diaphragm, and baffle means offering a tortuous path to sound waves emanating from the rear surface of said diaphragm.

65 2. In a sound-producing device, a dia-

phragm, actuating means therefor, and a plurality of baffle-devices interposed in a path traveled by sound-waves between the front and the rear surfaces of said diaphragm.

3. In a sound-producing device, a diaphragm, actuating means for said diaphragm, and a plurality of baffle-devices surrounding the rear surface of said diaphragm, said baffle devices cooperating to define a tortuous sound-passage from the rear surface to the 75 front surface of said diaphragm.

4. In a sound-producing device, a diaphragm, actuating means for said diaphragm, and a plurality of baffle-devices surrounding the rear of said diaphragm, said baffle-devices 80 cooperating to define a sound passage of gradually increasing area.

5. In a sound-producing device, a diaphragm, actuating means for said diaphragm, and a plurality of baffle-devices surrounding 85 the rear of said diaphragm, said baffle devices cooperating to define a tortuous sound passage having an approximately exponential increase in area.

6. In a sound-producing device, a diaphragm actuating means for said diaphragm, and a plurality of baffle-devices surrounding the rear of said diaphragm, said baffle-devices cooperating to define a tortuous sound 90 passage having a length at least approximately equal to one quarter wave length of the longest useful sound wave to be produced thereby.

7. In a sound-producing device, a diaphragm, actuating means for said diaphragm, 100 and a plurality of baffle devices surrounding the rear of said diaphragm, said baffle-devices comprising concentric partitions.

8. In a sound-producing device, a substantially freely suspended diaphragm, and 105 a plurality of concentric baffle devices associated with the rear of said diaphragm, certain of said baffle-devices being arranged in nested relation to define a tortuous sound-passage.

9. In a sound-producing device, a base, a diaphragm-mounting element, a substantially freely-movable diaphragm mounted on said element, and a plurality of concentric baffle devices surrounding the rear of said 115 diaphragm, certain of said devices being supported from said base and certain of said devices being supported from said element.

10. In a sound-producing device, a base, a diaphragm-mounting element affixed thereto, a substantially freely-movable diaphragm mounted on said element, and a plurality of concentric baffle-devices surrounding the rear of said diaphragm, certain of said devices being supported from said base and 120 certain of said devices being supported from said element, at least two of said baffle-devices being arranged in nested relation to define a tortuous sound passage.

11. In a translating device, a diaphragm, 130

a plate support for the edge portion of said diaphragm, and a mounting device for said plate support, said plate support being curved outwardly with reference to said mounting device to define an air passageway rearwardly of said diaphragm that increases in area approximately exponentially.

In testimony whereof, I have hereunto subscribed my name this 5th day of October, 1927.
